Primary Examiner — Kevin K Rudzinski*Assistant Examiner* — Cole Sanders Holman(74) *Attorney, Agent, or Firm* — Viering, Jentschura & Partner mbB(57) **CLAIM**

The ornamental design for a keyboard as shown and described.

DESCRIPTION

FIG. 1 is a perspective view of a keyboard showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the Figures show portions of the keyboard that form no part of the claimed design.

1 Claim, 5 Drawing Sheets(56)
